MEANS FOR MOVING AND DISTRIBUTING
FREE FLOWING MATERIALS

Erich Rahlson, Des Moines, Iowa

Application June 9, 1950, Serial No. 167,105

11 Claims. (Cl. 198—46)

1

My invention relates to the art of moving and distributing free flowing materials and has special application to the moving and distributing of small grain, corn, seeds or the like in the operation of grain elevators although its application is not necessarily confined to that field of endeavor.

More specifically my invention is concerned with an improvement whereby the time for moving and distributing any given load from one point to another is greatly reduced without requiring additional machinery. With particular reference to grain elevator operations my invention is designed to more efficiently use existing grain elevating equipment in the movement of grain to or from dryers, scales, cleaners or the like in a manner not heretofore accomplished.

The definition of certain terms here at the outset will facilitate the discussion to follow and for that purpose the word "house" has reference to the tower-like structure in which grain is stored and in which there may be several different storage bins. There is grain elevating machinery within the "house" to carry the grain to the top of the several bins for filling. Also, aside and apart from the "house," there is other grain elevating machinery for moving grain to and from the house and dryers, cleaners, scales, or the like. The word "elevator" when used herein has reference to this grain elevating machinery last mentioned.

Elevators are found in several different types and perhaps the most commonly known varieties embrace the bucket elevators, the pneumatic tube and the auger or screw-lift type. Of these, the bucket type in actual operations, is believed to be more widely used since they are considerably less expensive and therefore in my drawings I have chosen that type to illustrate the use of my invention, although it is not limited to that one species of elevators.

The modern elevator is frequently used with other grain processing devices such as dryers, cleaners, scales and the like and my invention has special utility in the means used for moving grain or the like to and from the house and these other devices. For purposes of simplicity in defining this invention, I have preferably chosen the use of the dryer and have illustrated the dryer and its use in my drawings. It is pointed out, however, that my invention is not intended to be limited to use with grain drying equipment only.

As with elevators, the dryer may be found in various types of construction and operation and

the particular form of dryer used is not material to the use of my invention.

In the operation and use of a grain dryer, there is usually a means for moving the grain from the house to the boot section of an elevator and a means for returning the grain from the dryer to the boot section of a second elevator. Such means may be belt, screw conveyor, drag or the like and is not here material. Also, there will be a means for delivering the grain from the elevator to the dryer. Two elevators are generally used in this situation and sometimes they are independent units separately operated and sometimes are mounted adjacent each other and operated by the same source of power and in still other cases the dual elevating machinery is found in a common housing and operated by the same source of power. This latter arrangement I have preferably used to illustrate my invention. With the bucket type elevator which I have shown in my drawings we find two sets of chains or belts each carrying a plurality of spaced apart buckets. The buckets on each respective belt usually travel in enclosed housings known as "legs" and the leg for each elevator will have two chambers separated by partition so that the buckets travel upwardly in one chamber and downwardly in the other. These are often referred to as the "up" leg and the "down" leg respectively. When two elevators are used as referred to above, the leg construction is duplicated and the legs for the two elevators are adjacent each other. This double elevator arrangement is a common form of construction and is known as "dual legging" to distinguish it from "double legging" or "double stacking" which has reference to a single elevator where the buckets travel in a two chambered leg. The "dual legging" thus is nothing more than two adjacent "double legs." In the two elevator arrangement, the belts operate on dual pulleys each in a single housing that are respectively located at the top and bottom of the elevator structure. A single motor usually mounted in the elevator head operates both pulleys and consequently both sets of buckets move simultaneously in the same direction and at the same speed.

The grain drying equipment is, of course, used to reduce the moisture content of the grain so that it can be better stored and preserved. As previously pointed out, these dryers vary in construction and operation and the particular type used is not material to my invention. However, in the present state of the art, the dryer functions substantially as follows: Wet grain to be dried is fed from a source of supply such as a wet

storage bin in the house or the like to the elevator. From there it is carried to a distribution point for delivery to the dryer. After the grain has passed through the dryer which may be by gravity or power, it is fed back to the elevator and carried to the distribution point for delivery to a dry storage bin. Normally in the drying operation, the grain at the top level of the batch will be dried by the time it leaves the dryer, but when the grain is initially placed in the dryer, a good portion thereof passes out while it is still wet. Obviously, it must be re-run through the dryer and my invention embodies means for this purpose.

In this drying process which I have just described generally it is pointed out that the two endless belts carrying buckets in the dual legging operate continuously and simultaneously since they are both connected to dual pulleys in single heads and are operated by the same power unit. The reason for this continuous operation at a constant speed is economy in operation. To provide variable speeds or intermittent operation would necessitate additional equipment and more personnel which would considerably increase the costs of operating the elevator. However, the buckets on one belt only are used for carrying the wet grain to the distribution point and likewise, the grain after leaving the dryer is carried in the buckets on only one belt back to the distribution point for delivery to the dry storage bin. This is of necessity true because in present type elevator installations the hoppers on opposite sides of the boot section each communicate respectively with only one set of buckets. Consequently grain fed into the boot from the wet bin falls into the buckets on only one belt and the same is true of dry grain fed from the dryer back to the hopper for movement ultimately to the dry storage bin. Obviously therefore, when the dryer is being initially filled, the buckets on only one belt are being used while the buckets on the other belt travel a parallel course and are empty. Also, when it is desired to completely empty the dryer, the grain is carried therefrom for delivery to the dry storage bin by the buckets on only one belt while the other buckets travel their course and are empty.

Since the buckets on any given elevator travel constantly and at a given speed, the length of time it takes to fill or empty the dryer is determined by the unit bushel per hour capacity of the particular buckets on one endless belt. It is of course possible to speed up the buckets but even if this is done the time for filling or emptying is still determined and limited by the capacity of the buckets on the one belt. This is likewise true on elevators other than the bucket type when the two elevator construction is used. The time element involved in this operation is very material from a standpoint of expense in elevator operation and any savings of time that could be effected would increase considerably the ability of any given elevator to dry a larger amount of grain in any given time.

With these problems and drawbacks of the present state of the art in mind, it is an object of my invention to provide in a system for moving and distributing free flowing materials, which system embodies the use of a pair of material handling devices that are adjacent each other and that operate simultaneously and in which one of such devices normally carries material to a distribution point for delivery to a point of deposit and the other like device carries the ma-

terial from said deposit point to a point of distribution for delivery to a second deposit point, a means whereby both of such devices can be respectively adapted at times to simultaneously carry the material to or from either point of deposit and thereby double the material moving capacity of such devices and consequently considerably shorten the time interval normally required for such operation.

10 More particularly my invention is adapted for use with grain elevators that are operated in conjunction with other grain processing equipment such as dryers, cleaners, scales or the like and wherein a dual set of elevators are used with one elevator only normally operating in the movement of grain to such processing device and the other elevator only being used in the movement of grain from such processing device to a place of storage. It is thus, the aim of my invention to make use of both elevators for moving the grain to or from such processing devices at times.

More specifically in accomplishing the objects above set forth it is my aim to provide first, two hoppers that are respectively mounted on opposite sides of the elevator boot, and each of which is designed to communicate with both sets of elevators on the respective sides, and a hopper selector device for each hopper whereby grain delivered to either hopper can be selectively directed into either or both sets of elevators, and secondly, a discharge box in the head of the elevator that is capable of communicating with each set of elevators and which has an adjustable divider or flipper plate whereby grain delivered to this box by either or both of the elevators separately or simultaneously can be selectively directed to a common point of deposit.

40 A further object of my invention is to provide improvements in grain elevating machinery having the capabilities above described that also makes possible the use of the elevator for continuous or batch drying without the need for additional special equipment.

45 A still further object of this invention is to provide a hopper selector and discharge box selector for use as set forth in which the selective adaptations possible can be quickly and easily manually accomplished without the use of any tools.

50 These and other objects will be apparent to those skilled in the art.

55 My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of a dual legging grain elevator construction that consists of two adjacent legs each having two chambers, which unit is shown embodying the use of my hopper selector on each side of the boot portion and my discharge box just below the elevator head,

60 Fig. 2 is a cross-sectional view of my discharge box taken on the line 2—2 of Fig. 1,

Fig. 3 is a cross-sectional view of the hopper and hopper selector taken on the line 3—3 of Fig. 1,

70 Fig. 4 is a diagrammatic view showing a storage house for grain with compartments for wet and dry grain, elevators, drying tower, discharge box and conveyors with directional arrows to indicate the flow of wet grain when the dryer is being initially filled. Also in this figure are

enlarged diagrammatic views of the hopper selector and discharge box with directional arrows to more clearly illustrate the flow of grain therethrough as represented in this Fig. 4,

Fig. 5 is a top view of one of the hopper selectors showing the selector plate positioned to direct grain into the right leg as seen in this drawing,

Figs. 6, 7 and 8 are each diagrammatic drawings showing the basic elements of Fig. 4 and in which Fig. 6 has directional arrows indicating the flow of grain when the dryer is being operated for continuous drying; Fig. 7 illustrates the flow of grain when the dryer is being emptied and no wet grain is entering the lifts; and Fig. 8 shows the flow of grain for re-running through the dryer or for what is known as batch dryer. In each of the Figs. 6, 7 and 8 enlarged diagrammatic drawings of the hopper selector and discharge box are shown to more clearly illustrate their use and operation.

Referring now to the drawings, the diagrammatic view of Fig. 4 illustrates one form of organization for grain elevator operations for which my invention is adapted. The numeral 10 designates a grain storage house which may be divided into different bins and which may have the dry grain bin 11 and wet grain bin 12 as illustrated. Elevating machinery is shown at 13 and at the top thereof is placed a discharge box 14 from which the spouts 15, 16, and 17 respectively extend to the dry bin 11, wet bin 12 and the drying tower 18. At the bottom of the elevator 13 is found the boot 19 which has the hopper 20 that receives grain from the wet bin 12 by an endless belt 21 and a like hopper 22 on the opposite side of the boot 19 which receives grain from the dryer 18 by the endless belt 23.

While I have shown belt means at 21 and 23, some installations may use screw conveyors or drags for this purpose or may even provide a gravity flow. The means for feeding the grain to the elevator boot is not, however, material to the use of my invention.

A heating unit 24 is connected with the dryer to circulate hot air about the grain as it passes through the drying tower 18. The use of the hoppers 20 and 22 and the discharge box 14 in connection with this form of organization embodies the features of my invention and the details for these structures are specifically illustrated in Figs. 1, 2 and 3. In Fig. 1 the elevator 13 consists of the substantially rectangular boot housing 19, the head section 25 and the vertical elevator legs 26, 27 and 28, respectively, that extend between the boot and head and communicate therewith. A fourth leg 29 not shown in Fig. 1 can be seen in Figs. 4, 6 and 7. While I have given separate numbers to the legs 26 to 29 inclusive for the purpose of clarity in description, the legs 26 and 27 are in effect the two chambers of one double leg or double stacking. The same is true of the legs 29 and 28 and the combination of the four constitute what I have referred to as dual legging. An endless belt 30 mounted around pulleys in the head 25 and boot 19 carries a plurality of spaced apart buckets 31 and is rotated by a motor usually located in the head so that the buckets 31 move up the leg 26 and down the leg 27. This is sometimes referred to as the "wet leg" as normally the wet grain from the wet bin is delivered to this series of buckets for movement to the dryer. Likewise the leg 28 is sometimes referred to as the "up"

leg and the leg 27 as the "down" as mentioned previously. The belt 32 with the buckets 33 is similarly arranged as the belt and buckets 30 and 31 and moves up the leg 29 and down the leg 28. Both series of buckets are powered by the same motor in the elevator head and run off dual pulleys in single heads so that they both move in the legs simultaneously and at the same speed and in the same directions. The second series of buckets 33 normally receives the dry grain from the dryer and is consequently referred to at times as the dry leg.

At the bottom of the elevator 13 there are the hoppers 20 and 22 being mounted on opposite sides of the boot 19 with the hopper 20 communicating with the up side of both series of buckets and the hopper 22 communicating with both sides on the down side thereof. In the present state of the art, the hopper on the up side communicates only with the wet leg and the one on the down side only with the dry leg. Because of this arrangement, moist grain from the wet bin is fed into a hopper that can deliver it to only one series of buckets and dry grain from the dryer is fed into a hopper that can deliver it only to one series of buckets. As a result the time required to fill or empty the dryer is determined by the capacity of buckets on only one belt while at the same time the buckets on the other belt run empty. The use of the buckets on both belts for filling or emptying the dryer is therefore one of the aims of my invention. This is accomplished by my hopper selector and discharge box which I will now describe.

The hoppers 20 and 22 are of the usual type having the open top and inclined surface as shown in Fig. 1. However, as described above, each of these hoppers on its respective side of the boot 19 communicates with both series of buckets 31 and 33 at its respective position. Secured to the open top of each hopper 20 and 22 is a vertical rectangular open bottom hopper selector 34 and 35 respectively as shown in figure. The top of these hopper selectors are shown with open tops for purposes of illustration, but it is pointed out that it may be desired to provide a cover for them especially if they are located out-of-doors. A portion of each outer side of each hopper at the top thereof is preferably cut away as at 36 to receive grain from the belts 21 and 23. On opposite sides of each hopper I provide a slot 37 transversely its height in which there is slidably arranged the selector plates 38 and 39, respectively. By inserting those plates in the slots on either side of the hopper selectors, communication with one or the other of the series of buckets is closed as illustrated in Figs. 3 and 5. By removing the plates entirely from the selectors, grain delivered thereto will be able to be picked up by both series of buckets. When the selector plates are used, the inner end drops downwardly to close off access to one series of buckets for which the grain is intended. The outer end of each plate 38 and 39 is bent to form the stop lips 40 and 41 so that the plate will not fall into the hopper when positioned as shown in Fig. 3. These plates are easily positioned or removed as described and this can be done manually without the need for any tool. The construction of these hopper selector plates embody but one form of device to selectively direct the flow of grain as described. It is possible to use flipper plates or the like for this purpose without departing from the object of my invention.

The discharge box 14 referred to above com-

prises a casing 42 having a plurality of conical shaped exits 43, 44 and 45, respectively, in the bottom thereof and adjacent each other as shown in Fig. 2. The casing 42 is mounted at the top of the elevator 13 and is secured to and communicates with the underside of the head 25 so that as the buckets 31 and 33 pass through the head toward the down legs, the grain therein will be dumped into the discharge box as indicated by the arrows in Fig. 4. The exits 43, 44 and 45 respectively communicate with the spouts 16, 17 and 15 so that grain from the discharge box can at times flow therefrom to either the wet or dry bins or to the dryer. Within the casing 42 there is a baffle member 46 extending downwardly and inwardly in the path of flow of grain falling from the buckets 31 as shown in Fig. 2. A stop member 47 extends downwardly into the casing 42 from a point adjacent the outside edge of the line of travel of the buckets 33. A movable flipper plate 48 is pivotally secured between the exits 44 and 45 and extends transversely the length of the casing. This plate 48 is manually movable by the means of the chain 49 secured to the control bar 50 to direct the passage of grain out of the discharge box as follows. As shown in Fig. 2 the flipper plate 48 engages the stop member 47 so that the discharge from both series of buckets will flow out either exits 43 or 44. In the enlarged diagrammatic sketch of the discharge box in Fig. 6 the plate 48 is shown in vertical position whereby grain from the wet leg flows through exit 44 and grain from the dry leg flows through exit 45. The corresponding diagram in Fig. 7 illustrates the plate 48 when engaging the baffle 46 so that the discharge from both series of buckets flow through exit 45.

Thus constructed and arranged as herein described, my improved system and means therefore for the movement and distribution of free flowing materials will operate in the following manner.

The wet or moist grain to be dried which is in the storage bin 12 must be transferred to the dryer tower 18. This is accomplished by removing the grain from the bottom of the bin on the belt 21 and feeding it into the hopper selector 34. If the dryer is being loaded initially, the quicker this can be done, the more time is saved and the sooner the drying can commence. Therefore, by removing the selector plate 38 from the hopper selector 34 grain from the wet bin 12 is carried on the feed means 21 and is delivered to the up side of both series of buckets 31 and 33, thereby doubling the loading capacity and halving the time normally found in present type operations.

The buckets 31 and 33 will carry the moist grain to the elevator head 25 where as they start downwardly the grain is spilled into the discharge box 14. The upper entrance into this box is in communication with both series of buckets 31 and 33 and the barrier 48 when positioned as shown in Figs. 2 and 4 closes off the exit 45 to the dry bin 11. The baffle member 46 aids in deflecting the grain toward the exit 44 from which the spout 17 carries the grain by gravity to the drying tower 18. When the dryer is full the grain will begin to pile up within the box 14 above the exit 44 as indicated by the curved dotted line in Fig. 2 and as grain continues to be delivered to the discharge box the grain will overflow into exit 43 and be carried by the spout 16 back to the bin 12.

Once the dryer has been filled and the drying

process commenced the hopper selector plates and flipper plate 48 in the discharge box are arranged as illustrated in Fig. 6. The normal drying operation contemplates moist grain carried from the bin 12 up one leg only to the discharge box to be fed into the dryer and dry grain being carried from the bottom of the dryer up one leg only to the box 14 for delivery to the dry bin 11. This is accomplished by positioning the selector plate 38 in the hopper selector 34 so that it closes off access by the wet grain to the buckets 33 and delivers it only to the up side of the buckets 31. In the discharge box the flipper plate is positioned between the two series of buckets so that grain entering from the wet bin in buckets 33 is directed toward exits 44 and 43 and grain entering from buckets 31 is directed to exit 45 to return to dry storage. For this operation the selector plate 39 in selector 35 is arranged to close off access of the dry grain to the buckets 31 and deliver it only to buckets 33 which carries it to the box 14 for delivery to exit 45 as stated above. Dry grain is, of course, fed from the bottom of the dryer to the elevator by the belt 23. This operation as shown in Fig. 7 is referred to as continuous drying.

For a re-run of wet grain through the dryer or for what is known as batch drying, reference is made to Fig. 8. This procedure contemplates re-running the dryer load of grain through the dryer without taking more wet grain from the bin 12. To accomplish this the outlet from bin 12 to the conveyor 21 is closed and the selector plate 39 for the hopper 22 is either removed or positioned to close off either of the buckets 31 or 33. Normally in a re-run the grain taken from the dryer will not travel at a speed necessitating the use of both series of buckets. Therefore, I show in Fig. 8 grain from the dryer being delivered to the wet buckets 31 for redelivery to the discharge box in which the flipper plate 48 is positioned as in Fig. 7 so that grain from the wet buckets falls into exit 44 and back to the dryer. The use of the buckets 31 here is merely a matter of choice and buckets 33 could be used by positioning the barrier 48 as shown in Fig. 2.

When it is desired to completely empty the dryer such as when all moist grain has been emptied from bin 12, or otherwise, the arrangement as shown in Fig. 7 is used. There, the outlet from bin 12 to conveyor 21 is closed if a supply of wet grain remains therein and the selector plate 39 is removed from the hopper selector 35. This permits the conveyor 23 to deliver grain from the bottom of the dryer to both series of buckets through hopper 22. The flipper plate 48 is positioned as shown in Fig. 7 so that it overlaps and engages the top of the baffle 46 and thereby closes all exits from the box 14 except 45 to grain delivered to this point by both series of buckets. Consequently, the grain emptied from the dryer will be delivered to the dry bin 11 and the capacity of both buckets 31 and 33 is available to materially shorten the time required for this operation over present methods.

The saving in time brought about by my invention herein disclosed is of considerable importance to grain elevator operations especially where man power, time and expense are important factors. By using my invention, an elevator operator can now accomplish more in one working day than was heretofore possible. Likewise, the shortening of the time element permits better service to customers and enables the oper-

ator to more efficiently handle business especially in rush seasons.

The use of the elevators as described is substantially the same when processing equipment such as cleaners, scales and the like is used. With cleaners, for example, the dirty and clean grain is moved respectively as hereinbefore described for wet and dry grain with dryers and my hopper selectors and discharge box can be effectively used in these other type of operations.

Some changes may be made in the construction and arrangement of my means for moving and distributing free flowing materials without departing from the real spirit and purpose of my invention, and it is my intention to cover by my claims, any modified forms of structure or use of mechanical equivalents which may be reasonably included within their scope.

I claim:

1. In a system for moving and distributing free flowing materials, a pair of material handling devices that are adjacent each other and that operate simultaneously and each having a material receiving end and a material discharging end, a hopper positioned at the receiving end of said material handling devices and capable of communicating with each of said devices, a means within said hopper for selectively closing the communication between said hopper and either of said material handling devices, a discharge box positioned at the discharge end of said material handling devices, a plurality of exits in said discharge box, and means within said discharge box for selectively directing the flow of materials from either of said devices at times and from both of said devices at times through one or more of said exits.

2. In a system for moving and distributing free flowing materials; a pair of material handling devices that are adjacent each other and that operate simultaneously and each having a material receiving end and a material discharging end, a hopper positioned at the receiving end of said material handling devices and capable of communicating with each of said devices, a selector plate within said hopper capable of closing the communication between said hopper and either of said material handling devices, a discharge box positioned at the discharge end of said material handling devices, a plurality of exits in said discharge box, and a flipper plate member hingeably secured within said discharge box and capable of directing the flow of materials from either of said devices at times and from both of said devices at times through one or more of said exits.

3. In a system for moving and distributing small grain, corn, seed or the like, in a grain elevator installation, comprising; a dual set of grain elevating machinery that operates simultaneously; each of said sets of grain elevating machinery having a grain receiving end and a grain discharging end, a hopper positioned at the receiving end of said sets of grain elevating machinery and capable of communicating with each of said sets of grain elevating machinery, a means within said hopper for selectively closing the communication between said hopper and either of said sets of grain elevating machinery, a discharge box positioned at the discharge end of said sets of grain elevating machinery, a plurality of exits in said discharge box, and means within said discharge box for selectively directing the flow of grain from either of said sets of grain elevating machinery at times and from

both of said sets of grain elevating machinery at times through one or more of said exits.

4. In a system for moving and distributing small grain, corn, seed or the like, in a grain elevator installation, comprising; a dual set of grain elevating machinery that operates simultaneously; each of said sets of grain elevating machinery having a grain receiving end and a grain discharging end, a hopper mounted on said grain receiving ends and capable of communicating with each set of grain elevating machinery, a hopper selector plate arranged within said hopper and capable of being selectively positioned to close the communication between said hopper and either of said sets of grain elevating machinery, a discharge box mounted on said grain discharging ends and having an entrance communicating with each of said sets of grain elevating machinery, a plurality of exits in said discharge box and a flipper plate member hingeably secured at one end between two adjacent exits within said discharge box and capable of selectively directing the flow of grain from either and both of said sets of grain elevating machinery through one or more of said exits.

5. In a system for moving and distributing grain, corn, seed or the like, a dual set of elevators that operate simultaneously; each of said elevators having adjacent receiving ends and adjacent discharging ends, a hopper mounted on said receiving ends and capable of communicating with either of said elevators, means within said hopper for selectively closing the communication between said hopper and either of said elevators; said means being removable whereby said hopper is in communication with both of said elevators, a discharge box mounted on said discharging ends of said elevators and having an entrance communicating with each of said elevators, a first exit in said discharge box designed to direct the flow of grain to a point of deposit, a second exit in said discharge box designed to direct the flow of grain to a second point of deposit, a third exit in said discharge box designed to direct the flow of grain to a third point of deposit, and means within said discharge box capable of directing the flow of grain from said discharging end of either or both of said elevators into said first and second exits at times and into said third exit only at times.

6. In a system for moving and distributing grain, corn, seed or the like, a dual set of elevators that operate simultaneously; each of said elevators having adjacent receiving ends and adjacent discharging ends, a hopper mounted on said receiving ends and capable of communicating with either of said elevators, a hopper selector plate slidably mounted within said hopper and capable of closing the communication between said hopper and either of said elevators; said hopper selector plate being removable whereby said hopper is in communication with both of said elevators, a discharge box mounted on said discharging ends of said elevators and having an entrance communicating with each of said elevators, a first exit in said discharge box designed to direct the flow of grain to a point of deposit, a second exit in said discharge box designed to direct the flow of grain to a second point of deposit, a third exit in said discharge box designed to direct the flow of grain to a third point of deposit, and means within said discharge box capable of directing the flow of grain from said discharging end of either or both of said elevators

into said first and second exits at times and into said third exit only at times.

7. In a system for moving and distributing grain, corn, seed or the like, a dual set of elevators that operate simultaneously; each of said elevators having adjacent receiving ends and adjacent discharging ends, a hopper mounted on said receiving ends and capable of communicating with either of said elevators, a hopper selector plate slidably mounted within said hopper and capable of closing the communication between said hopper and either of said elevators; said hopper selector plate being removable whereby said hopper is in communication with both of said elevators, a discharge box mounted on said discharge ends of said elevators and having an entrance in the top thereof communicating with each of said elevators, a first exit in the bottom of said discharge box designed to direct the flow of grain to a point of deposit, a second exit in the bottom of said discharge box designed to direct the flow of grain to a second point of deposit, a third exit in the bottom of said discharge box designed to direct the flow of grain to a third point of deposit, a flipper plate member hingeably secured at one end within said discharge box at a point intermediate said first and third exits, means for facilitating the manual movement of said flipper plate to different positions; said flipper plate capable of being moved to direct the flow of grain from said discharge end of either or both of said elevators into said first and second exits at times and into said third exit only at times.

8. A discharge box designed to be mounted on the discharge end of a dual set of elevators in a grain elevator installation, an entrance in said discharge box designed to communicate with the discharge end of either and both elevators of a dual elevator arrangement, a plurality of exits in said discharge box, and means within said discharge box designed to selectively direct the flow of grain from either of said sets of elevators at times and from both of said sets of elevators at times through one or more of said exits.

9. A discharge box designed to be mounted on the discharge end of a dual set of elevators in a grain elevator installation, an entrance in said discharge box designed to communicate with the discharge end of either and both elevators of a dual elevator arrangement, a first exit in said discharge box designed to direct the flow of grain to a point of deposit, a second exit in said discharge box designed to direct the flow of grain to a second point of deposit, a third exit in said discharge box designed to direct the flow of grain to a third point of deposit, and means within

said discharge box capable of directing the flow of grain from said discharge end of either or both of said elevators into said first and second exits at times and into said third exit only at times.

- 5 10. In a system for moving and distributing free flowing materials, a pair of material handling devices that are adjacent each other and that operate simultaneously and each having a material receiving end and a material discharging end, a hopper positioned at the receiving end of said material handling devices and capable of communicating with each of said devices, a means within said hopper for selectively closing the communication between said hopper and either of 15 said material handling devices; said means being removable whereby said hopper is in communication with both of said devices, a discharge box positioned at the discharge end of said material handling devices, a plurality of exits in said discharge box, and means within said discharge box for selectively directing the flow of materials from either of said devices at times and from both of said devices at times through one or more of said exits.
- 20 25 11. In a system for moving and distributing free flowing materials, a pair of material handling devices that are adjacent each other and that operate simultaneously and each having a material receiving end and a material discharging end, a hopper positioned at the receiving end of said material handling devices and in communication with both of said devices, means associated with said hopper for selectively closing the communication between said hopper and either of said material handling devices, a discharge box positioned at the discharge end of said material handling devices, a plurality of exits in said discharge box, and means within said discharge box for selectively directing the flow of materials from either of said devices at times and from both of said devices at times through one or more of said exits.
- 30 35 40
